JOURNAL BOX CONSTRUCTION FOR
RAILWAY CARS

Edward Payson Smith, Winnetka, Ill., assignor to Illinois
Railway Equipment Co., Chicago, Ill., a corporation of
Illinois

Filed Aug. 30, 1962, Ser. No. 220,431
8 Claims. (Cl. 308—40)

This invention relates, generally, to railway car journals and it has particular relation to exterior radial bearing supports therefor. It constitutes an improvement over the constructions shown in application Serial No. 177,079, filed March 2, 1962, by Theodore A. Sweger, and assigned to the assignee of this application.

Among the objects of this invention are: To provide in a new and improved manner for mounting journal guides between the inner sides of a railway car journal box and the opposite sides of an axle journal therein; to support the journal guides on the ends of energy storing means, such as a collapsible spring, which functions to hold them in operative position; to hold the spring in collapsed condition whereby application of it and of the journal guides to the journal box is facilitated; to release the collapsed spring when it and the journal guides have been inserted in the journal box to permit it to expand and position the journal guides in operative positions on opposite sides of the axle journal and to hold them in such position; to employ a spring having a series of reverse turn sections of spring wire; to terminate the spring wire series of reverse turn sections in loops that surround the respective journal guides; to provide integral spaced arms from the loops for engaging opposite vertical sides of wedge guide columns on the side walls of the journal box for the purpose of centering the journal guides; to enclose the reverse turn sections of the spring in a collapsible envelope having a hem along its periphery; to provide a drawstring in the hem of the envelope for collapsing it and holding it and the reverse turns of the spring therein in collapsed condition; and to bring out the ends of the drawstring from the hem intermediate one side of the envelope.

In the drawings:

FIG. 1 is a top plan view of a collapsible one piece spring wire retainer enclosed in an envelope and having the journal guides at the ends, the construction being shown in the expanded condition.

FIG. 1A is a vertical cross sectional view, at an enlarged scale, taken generally along the line 1A—1A of FIG. 1.

FIG. 2 is a view, in side elevation, of the construction shown in FIG. 1.

FIG. 3 is a view, partly in end elevation and partly in vertical section and looking from left to right of FIG. 6, showing certain details of construction of a journal box in which the present invention is employed.

FIG. 4 is a top plan view, similar to FIG. 1, but showing the one piece spring wire and the envelope therefor in collapsed condition.

FIG. 5 is a view, in side elevation, of the collapsed construction shown in FIG. 4, showing by broken lines the positions assumed by the collapsed construction when it is inserted in the bottom of the journal box and before it is released for expansion to operative position.

FIG. 6 is a vertical sectional view, taken generally along the line 6—6 of FIG. 3, the wedge and journal bearing being omitted.

Referring now particularly to FIGS. 3 and 6 of the drawings, it will be observed that the reference character 10 designates, generally, a railway car axle which has an axle journal 11 which is provided with an end collar 12. The longitudinal axis of rotation of the railway car axle 10 is indicated at 13. The railway car axle 10 is located in a railway car journal box that is indicated, generally,

2

at 14 and is of conventional construction. It includes a generally horizontal top wall 15, side walls 16—16, a concave bottom wall 17 and a concave end wall 18, the upper side of which forms the lower margin of a lid opening 19 (the lid not being shown). At the other end the journal box 14 has a dust guard well 20 which is formed by vertical walls 21 and 22. To the right of the axle journal 11 the railway car axle 10 has a hub portion 23 which projects beyond the vertical walls 21 and 22.

10 Depending from the end of the top wall 15 adjacent the lid opening 19 is a wedge stop 25 that is provided for holding a flat back wedge 26, FIG. 3 in operative position, on top of a flat back journal bearing 27 which has a lining 28 of bearing metal which overlies the upper portion of 15 the axle journal 11 and through which the weight of the railway car applied to the journal box 14 is transmitted to the railway car axle 10. The wedge 26 is held against lateral displacement between wedge guide columns 29—29 that are formed integrally with an extend from the inner 20 sides of the side walls 16—16.

As pointed out in the copending application above referred to, the construction thus far described is arranged to have the journal box 14 elevated sufficiently far to permit the wedge 26 to be withdrawn from underneath the 25 wedge stop 25. This also permits removal of the journal bearing 27 for replacement, inspection or the like.

It is desirable that relative lateral movement of the axle journal 11 with respect to the side walls 16—16 of the journal box 14 be prevented. For this purpose journal 30 guides 31—31 are provided. They may be formed of metal, such as brass either in whole or in part and are provided with base portions 32—32 which are arranged to bear against the inner sides of the side walls 16—16 at 35 positions immediately below the wedge guide columns 29—29. The journal guides 31—31 are of elongated configuration and have forward portions 33—33 that have faces 34—34 which are juxtaposed to diametrically opposite sides 35—35 of the axle journal 11.

Intermediate the base and forward portions 32—32 40 and 33—33 of the journal guides 31—31 are grooves 36—36 which are provided for receiving loops 37—37 of relatively heavy spring wire. It will be noted that the loops 37—37 are formed integrally at the ends of a collapsible one piece spring wire retainer that is indicated, 45 generally, at 38 in several of the figures of the drawings. The extreme ends of the spring wire are indicated at 39—39 and they extend laterally from the loops 37—37 as do relatively short loops 40—40. The ends 39—39 and the loops 40—40 are inclined slightly for the purpose 50 of bearing against the inner sides of the concave bottom wall 17 and of the side walls 16—16 when the assembly is applied to the journal box 14 as described hereinafter. The ends 39—39 and loops 40—40 are spaced apart to 55 overlie opposite vertical sides 41—41 of the wedge guide columns 29—29. Between the loops 37—37 the spring wire retainer 38 is in the form of a series of reverse turn sections 43 the number of which can vary depending upon the particular conditions that are to be met and the forces 60 that are to be exerted. They constitute energy storage means which energy can be released to position the journal guides 31—31 in their operative positions shown in FIG. 3. At the ends of the wire retainer 38 the reverse turn sections 43 terminate in parallel end sections 44—44 which 65 are also parallel to the loops 37—37 and the journal guides 31—31 carried thereby.

In order to store energy in the spring wire retainer 38 and hold the reverse turn sections 43 in the collapsed condition with energy stored therein, an envelope shown, generally, at 45 is provided. The envelope 45 is of rectangular configuration and preferably is formed of suitable high strength flexible plastic material such as polyethylene or

other heat sealing plastic. As shown in FIG. 1A the envelope 45 is formed by an upper layer 46 and a lower layer 47 of plastic material and here it is shown as overlying one of the return bends of the spring wire retainer 38 with the adjacent surfaces joined at 48 by a suitable heat sealing operation. The layers 46 and 47 are joined along their peripheries at 49 by a similar heat sealing operation in such manner as to provide a hem 50 in which a drawstring 51 is located. If desired, the drawstring can be inserted along the periphery of the upper and lower layers 46 and 47 after they have been joined at 48 by the heat sealing process. Subsequently the extreme outer edges of the upper and lower layers 46 and 47 are joined at 49 to enclose the drawstring 51 in the hem 50 thus formed.

As shown in FIGS. 1 and 4, the ends 52-52 of the drawstring 51 extend from the hem 50 intermediate one of the long sides of the envelope 45.

When the spring wire retainer is in the collapsed condition as shown in FIGS. 4 and 5, the envelope 45 is ruffled as indicated at 54 in FIG. 5. This is accomplished by pulling the ends 52-52 of the drawstring 51 outwardly through the one side of the envelope 45 while the spring wire retainer 38 is held in collapsed condition. The ends 52-52 of the drawstring 51 then are tied as indicated at 55 to hold the assembly in the collapsed condition with energy stored in the reverse turn sections 43 of the spring wire retainer 38.

When the assembly is in the collapsed condition, as shown in FIGS. 4 and 5, it can be inserted readily through the lid opening 19 of the journal box 14 and applied to the concave bottom wall 17 in the position as indicated by broken lines in FIG. 5. Then the knot at 55 is untied. This releases the envelope 45 and permits the reverse turn sections 43 of the spring wire retainer 38 to expand and to move the journal guides 31-31 upwardly to their operative positions underneath the wedge guide columns 29-29 with the ends 39-39 and loops 40-40 guided on their opposite sides. The journal guides 31-31 can be removed from the journal box 14 by reversing the foregoing steps.

For illustrative purposes the journal box 14 has been shown in conjunction with a flat back wedge 26 and a flat back journal bearing 27. It will be understood that the present invention can be employed with other types of journal boxes having other wedge and bearing constructions. If desired the construction can be such as to locate the journal guides 31-31 outwardly of the wedge guide columns 29-29. The usual waste (not shown) as can be applied in conventional manner in the lower part of the journal box 14 in overlying relation to the envelope 43

and the spring wire retainer in expanded condition on the concave bottom wall 17.

What is claimed as new is:

1. In a railway car journal box construction, said journal box having spaced vertical side walls with an axle journal in spaced relation therebetween, top and bottom walls interconnecting said side walls above and below said axle journal, a journal bearing overlying said axle journal, and a wedge interposed between said top wall and said journal bearing; the improvement which comprises: a journal guide interposed between each side wall and the diametrically opposite sides of said axle journal, endwise collapsible spring means supporting each journal guide in operative position in said journal box, means for holding said spring means in collapsed condition below said axle journal with said journal guides along said bottom wall to facilitate application of said journal guides in said journal box, and means for releasing said holding means whereupon said spring means expands along said bottom wall and moves said journal guides therewith to their operative positions.
2. The invention, as set forth in claim 1, wherein the spring means is in the form of a series of reverse turn sections of spring wire.
3. The invention, as set forth in claim 2, wherein the holding means is a collapsible envelope enclosing the spring means.
4. The invention, as set forth in claim 3, wherein the envelope has a hem along its periphery, and a drawstring in said hem is arranged and adapted to releasably hold the spring means in collapsed condition.
5. The invention, as set forth in claim 4, wherein the ends of the drawstring emerge from the hem intermediate one side of the envelope.
6. The invention, as set forth in claim 2, wherein the end sections of the spring wire terminate in loops surrounding the respective journal guides.
7. The invention, as set forth in claim 6, wherein each side wall of the journal box has a wedge guide column, and each loop has a pair of outstanding spaced arms overlying opposite vertical sides of the respective wedge guide column.
8. The invention, as set forth in claim 7, wherein one arm of each pair of arms is the extreme end portion of the spring wire and the other arm is an intermediate looped portion.
